UNITED STATES PATENT OFFICE

CHARLES T. MAGILL, OF CLARKDALE, ARIZONA

SPEED REDUCTION SIGNAL

Application filed July 14, 1927. Serial No. 205,675.

The invention relates to signalling means designed primarily for use on automobiles to give warning to following drivers that reduction in speed is to be made.

5 The principal object of my invention is to provide a speed reduction signal which is operatively connected with and controlled by pressure within a fluid circulating means of the machine on which the signal is used, said 10 fluid circulating means being preferably the means for circulating lubricating oil for the motor.

In carrying out the above end, a further object is to provide a unique pressure-controlled means for in turn controlling the signal.

With the foregoing in view, the invention resides in the novel subject matter herein-after described and claimed, the description 20 being supplemented by the accompanying drawings.

Fig. 1 is a diagrammatic perspective view showing the signalling means operatively related with an automobile.

25 Fig. 2 is a vertical section through the pressure-controlled signal-controlling means.

Fig. 3 is an enlarged sectional view through the central parts shown in Fig. 2.

Fig. 4 is a horizontal section on line 4—4 of 30 Fig. 3.

In the drawings above briefly described, the numeral 5 designates an automobile embodying the usual motor 6 having means for circulating lubricating oil, said means being 35 shown as embodying an oil pump 7 provided with an inlet 8 from the sump of the motor and with an outlet 9 leading to the usual oil distributing means. Mounted upon the automobile 5, is a speed reduction signal 10 of

40 any desired electrical nature. Appropriate wiring 11—12 and a cutout switch 13 are employed for the signal 10, and for controlling the circuit through the wiring, a pressure-controlled switch means 14 is provided.

45 When this switch means and the switch 13 are closed, current from the usual automobile battery 15 illuminates or otherwise operates or attracts attention to the signal 10, but as long as the machine is driven at substantially 50 a constant speed, or is increased from such

constant speed, the signal 10 does not come into play. Immediately however, upon reduction in speed from any at which the machine has been traveling, the switch 14 automatically acts to illuminate or otherwise 55 operate the signal 10, giving warning to any drivers behind, that the speed of the machine is being checked. This operation of the switch 14 is made possible, due to the fact that this switch is subjected to the oil pressure supplied to the motor by the pump 7, unique provision being made whereby the switch is held open by such pressure at any speed of the machine, yet is permitted to close upon reduction of such speed. 60

The particular form of switch herein disclosed, embodies two axially aligned cylinders 16—17 having a threaded connection 18 with each other at their inner ends, said inner end of the cylinder 16 being enlarged internally 70 to provide a space 19 within which certain contacts operate. A double-ended plunger 20 has its opposite ends mounted in the cylinders 16—17 respectively, and one or both ends of this plunger may be provided with packing rings such as 22. Cylinder 16 is provided with a pressure inlet 23 connected by a pipe or the like 24 with the discharge from the pump 7, so that the oil pressure within cylinder 16 and the oil circulating means of the 75 machine, will be uniform and such pressure will serve to force the plunger 20 toward the cylinder 17 to a greater or lesser extent, according to the speed of the motor 6. As plunger 20 moves further into cylinder 17, it compresses air in the latter, the air pressure thus counterbalancing the oil pressure and serving to hold the plunger 20 against movement as long as the motor is running at a uniform speed. As soon however as reduction 80 in speed is made, the oil pressure proportionately reduces with the result that the air pressure in the cylinder 17, forces the plunger 20 further into the cylinder 16. These movements of the plunger 20, effected by oil and air pressure, are relied upon to control the circuit of the signal 10. 85

Binding posts 25 are provided for the wiring 12, said posts passing through the enlarged inner end of the cylinder 16 and being 90 95 100

insulated therefrom. The inner ends of these binding posts carry contacts 26 of any desired form. These contacts are in the path of a movable switch member 27 within the chamber 19, said switch member having a frictional connection with the plunger 20. Preferably, the switch member 27 is in the form of a metallic shell surrounding an insulating ring 28 around the plunger, said shell and ring being split as at 29 in Fig. 4 and being of self-contracting nature to establish a frictional connection with said plunger.

When the motor 6 stands at rest, the switch member 27 engages the contacts 26 as shown in Figs. 2 and 3, but the signal 10 is then prevented from operating by opening the switch 13. Upon starting the motor, the switch 13 is of course closed. As soon as oil pressure reaches the cylinder 16, it elevates the plunger 20, causing the ring 28 which controls the switch member 27 to elevate this switch member out of engagement with the contacts 26, so that the signal 10 will not now be in operation. As the motor speed is increased, the plunger 20 is forced further upward and during such movement, it merely slides through the ring 28, the upward movement of this ring and its shell 27 being limited by the lower end of the cylinder 17. Thus, regardless of how much the speed of the machine be increased, the switch member 27 is held out of engagement with the contacts 26 and the signal 10 will not operate. However, immediately upon reduction of speed from that at which the machine has been operating, the compressed air trapped in the cylinder 17 by ascent of the plunger 20, comes into play to depress this plunger, such depression being permitted by reduction of oil pressure in the cylinder 16, incident to decrease of motor speed. This descent of the plunger 20 brings the switch member 27 against the contacts 26, completing the circuit of the signal 10 and bringing the latter into play, thus immediately giving warning that the speed of the machine is being checked.

Preferably, the contacts 26 are spaced apart about one hundred and twenty degrees and a "dead contact" 26^a is disposed between them. This arrangement prevents the contacts from having any tendency to cant the ring 28 on the plunger 20 with danger of binding.

Excellent results are obtainable from the general construction shown and described and such construction is therefore preferably followed. However, it is to be understood that the present disclosure is illustrative rather than limiting in a number of respects, and that within the scope of the invention as claimed, numerous variations may be made.

The particular switch shown in detail in Figs. 2, 3 and 4, is protected by my U. S. Patent 1,777,213 of September 30, 1930.

35 I claim:—

1. In an automobile, a motor, lubricating means for said motor having a pump driven by said motor, and a speed reduction warning signal for the drivers of following machines, and means controlled by the oil pressure out-put of said pump for operating said signal upon any decrease of motor speed, whereby any decrease of motor speed will operate said signal to give warning to the drivers of following machines.

2. In an automobile, a motor, lubricating means for said motor having a pump driven by said motor, said pump producing an oil pressure output which varies proportionately with motor speed, an electrical speed reduction warning signal for the drivers of following machines, a circuit for said signal embodying a switch, and means controlled by the oil pressure output of said pump for holding said switch open during motor speed increase to any desired speed and during maintenance of said speed, and for automatically closing said switch upon any decrease of motor speed, whereby any decrease of motor speed will operate said warning signal to give warning to the drivers of following machines.

In testimony whereof I have hereunto affixed my signature.

CHARLES T. MAGILL.
